PAPER FEEDING MECHANISM

Henry Resch, Bayonne, N. J., assignor, by mesne assignments, to Ralph C. Coxhead Corporation, New York, N. Y., a corporation of Delaware

Application August 15, 1931, Serial No. 557,236

9 Claims. (Cl. 197—127)

This invention relates to improvements in typewriting machines and more particularly to paper feeding mechanism therefor. It is in the nature of improvements which may be used with the device illustrated in the application of Frank H. Trego, Serial No. 399,733, filed Oct. 15, 1929.

The "Varietyper" writing machine, in connection with which the invention is herein illustrated, includes a set of feed rollers by which a work sheet may be fed upwardly between a type shuttle at the front thereof and a hammer at the back of the work sheet. Because of the fact that these feed rollers are located below the printing point, it has been impossible to type to the bottom edge of a work sheet.

An object of the present invention is to provide means whereby the work sheet is held so that the bottom edge thereof may be typed upon.

To this end there is provided a set of feed rollers, arranged above the printing point, by which the work sheet may be fed after it leaves the bite of the lower feed rollers and thus present the lower edge of the work sheet to the printing instrumentalities.

25 A feature of the invention relates to the positioning of the feed rollers so that the bite of the lower ones is in the same vertical plane extending through the bite of the upper ones and through the printing point, so that the work sheet may always be presented in a flat condition to the printing instrumentalities.

30 Some of the features of the invention relate to the manner of supporting the feed rollers, the means for releasing them and the means for spacing the work sheet with the feed rollers.

In carrying out the invention there is provided a rack or bracket, supported on the carriage above the printing instrumentalities, and upon which are supported the feed rollers. The rack is also 40 provided with one or more channel-shaped guides to hold the work sheet and to direct the work sheet to and away from said feed rollers.

The paper rack is pivotally supported on the carriage so that it may be swung rearwardly with the feed rollers and the paper guides thereon to lay the work sheet on an erasing shelf located behind the vertical plane in which the work sheet is fed to and from the printing point. Novel detents are provided to hold the paper rack in its various positions.

45 Another feature of the invention relates to channel-shaped guides which are formed to facilitate the insertion of a work sheet into the machine from the top of said guide.

Other features and advantages will herein-after appear.

In the accompanying drawings,

Fig. 1 is a front elevation of a portion of the carriage showing the invention applied thereto; 5

Fig. 2 is a vertical section of the carriage taken on the line 2—2 of Fig. 1;

Fig. 3 is a side elevation of a portion of the carriage and the paper rack with the feed rollers released; 10

Fig. 4 is a view similar to Fig. 3 showing the paper rack swung back to lay the work sheet on the erasing shelf; and

Fig. 5 is a detail sectional view taken on the line 5—5 of Fig. 3. 15

Similar characters refer to similar parts throughout the several views.

The invention is shown as applied to a "Varietyper" writing machine which includes a carriage 7 having a bar 8 by which it may travel back and forth, through the medium of rollers or balls 9, on a rail 10 secured to the main frame 11; the carriage being guided at its upper end by a bar 12, secured to end pieces 13 of the carriage. 20

A work sheet 14 may be fed up from a container 15 by feed rollers 16 and 17 to advance it between a printing hammer 18 and a type carrier or shuttle 19. The hammer 18 is arranged behind the work-sheet and is adapted to cooperate with types 20 of the type shuttle 19; the 30 shuttle being indexed to select the type in the usual manner by means including an actuator 21 operated by the character keys (not shown). The work sheet may be advanced from line to line by the usual line spacing mechanism including a line space wheel 22 secured to a shaft 23 to which the feed roller 16 is secured, said shaft 23 being rotatably supported in arms 24 secured to a shaft 25 pivotally supported in the end pieces 13 of the carriage. 35

The feed roller 16 is normally pressed against the other feed roller 17 by a spring 26 which may be coiled around the shaft 23 and acts on one of the roller supporting arms 24. 40

The feed rollers may be released in the usual manner by a release lever 27, the upper end of which may swing rearwardly about the shaft 23. The lower end of said release lever, which is in the form of a cam, engages a stud 28 on the end piece 13 of the carriage to carry the feed roller 16 rearwardly against the action of the spring 26, the stud 28 engaging in a notch 27a of the release lever to hold the latter in its operated position. 45

When the bottom edge of the work sheet is 55

about to leave the bite of the feed rollers 16 and 17, a set of upper feed rollers, indicated generally by the numeral 29, is brought into action as in Fig. 2. This set of feed rollers is supported above the printing instrumentalities, and is operable in a manner hereinafter described; the rollers of said set being normally released, as in Fig. 3, while the work sheet is being fed by the regular feed rollers 16 and 17.

10 While the work sheet is being fed by the lower feed rollers 16 and 17, that portion thereof above the printing line may be guided by a paper rack, indicated generally by the numeral 30, which includes two end pieces 31 secured to each other by horizontal rods or bars 32 and 33, each end piece 31 being supported on a stud, indicated generally by the numeral 34, (Figs. 1 and 5) secured to the carriage end 13 by a nut 35 threaded onto a shank 36 of the stud 34.

15 20 Supported on the bar 33 are two guides 37, one at each side of the work sheet 14. Each guide has a portion 38 bent up from its side edge of the body portion 39 to form a channel or groove 40 in which the work sheet is guided. Said guides are adjustable sidewise on the bar 26 according to the width of the work sheet and according to the position of the sheet lengthwise of the carriage. Each side guide is provided for this purpose with two ears 41 bent rearwardly therefrom and embracing the bar 33. Collars 42 secured to the bar 33 by screws 43 hold the end guides 37 in their adjusted positions.

25 30 A web 44 of each paper guide joins the portion 38 with the body part 39. This web is of considerable length and is used to square a fresh work sheet in the machine. The usual stationary line guides 45 may be used to position a work sheet in the machine at the printing line.

35 40 The set 29 of upper feed rollers includes two rear feed rollers 47 secured to a shaft 48 rotatably supported in the end pieces 31 of the paper supporting rack 30, the feed rollers 47 having each a metal core 47^a through which a set screw 47^b is threaded to secure the feed roller to the rod 48. The set 29 further includes forward feed rollers 49 rotatably supported on a rod 50 secured to arms 51 by screws 52; said arms and the rod 50 constituting a feed roller supporting frame which is pivotally supported on shouldered screws 53 by which the rod 32 is secured to the end pieces 31 of the paper rack.

45 50 Springs 54 are provided to act on the arms 51 of the feed roller frame to press the feed rollers 49 against the rear feed rollers 47 to firmly grip the work sheet 14. Each spring 54 is coiled around the rod 32 and one end thereof is anchored by a screw 55 threaded through a collar 56 and bearing against the rod 32. This provides a means of adjusting the spring to produce the desired pressure of the feed rollers 49 against the feed rollers 47. The feed rollers are held in position lengthwise of the rod 50 by collars 57 secured to the rod 50 by screws 58.

55 60 To line space the work sheet 14, by means of the feed rollers 47 and 49, there is provided, on the right-hand end of the shaft 48, a finger wheel or knob 59 by which said shaft may be rotated. The work sheet is located in line space position by a ratchet wheel 60 secured to the other end of the shaft 48, said ratchet being acted upon by a spring pressed detent 61 pivotally supported on the rod 33.

65 70 Provision is made for inserting the work sheet into the machine by passing it down through the side guides 37. To facilitate the entrance of the

work sheet into said guides, the upper free corner 62 of each of the forward portions 38 is flared outwardly to provide a wide mouth at the top of each channel 40 of the guide.

75 80 To release the upper feed rollers there is provided, at the right-hand end of the carriage, a lever 65 pivoted on a shouldered screw 66. The upper end of the lever 65 is provided with a finger piece so that it may be pushed rearwardly about the pivot 66 to cause the lower end 67, which acts 10 as a cam, to engage the end piece 51 of the feed roller supporting frame to swing the latter about its pivots 53 and carry the feed rollers 49 away from the feed rollers 47 from the position in Fig. 2 to the position in Fig. 3. The release lever 65 is 15 arrested in its operated position by a stud 68 and while in this position the end of the cam 67 is on, or slightly beyond, the dead center so that the feed rollers are locked in their released positions against the action of the springs 54. To cast on 20 the feed rollers 49 the release lever 65 is moved away from the stop 68; and after the end of the cam 67 moves off the dead center the springs 54 swing the feed roller supporting frame to carry the forward feed rollers 49 against the rollers 25 47 to grip the interposed work sheet.

25 30 An erasing shelf or table 70 is supported on the carriage over which the work sheet may be laid when an erasure is to be made. Said erasing shelf is located behind the plane in which the work sheet is normally disposed. Accordingly the paper rack 30 may be swung rearwardly about its pivot 34 to the position in Fig. 4. Stops 71 and 72 on each of the rack ends 31 engage a stud 73 on the carriage ends 13 to limit the movement of the 35 paper rack 30 to its active or inactive position (Figs. 3 and 4).

35 40 To hold the paper rack in its two positions there is provided on each pivot stud 34 a resilient detent 75 having a protuberance 76 to engage in either one of two apertures 77 and 78 on the end piece 31 of the paper rack. The detent is supported on the bearing portion 79^a of the stud and is held thereon by a head 79 of said stud. The width of the bearing portion is slightly greater 45 than the combined thickness of the end piece 31 and the detent 75 so as to permit freedom of movement of the end piece about the stud. To prevent turning of the detent with the end piece the detent is provided with two ears 80 which 50 engage the opposite sides of the rectangular head 79 of the fixed stud 34. This makes a simple and highly efficient detent which may be readily assembled without rigidly securing it to another element in the machine. Consequently it may readily be replaced by a new one at any time if necessary.

55 60 To assist in positioning the paper guides 37 at the desired letter space position on the carriage, there is provided a scale bar 85 secured to two 65 arms 51, of the pivoted frame which supports the feed rollers 49, by screws 86. The usual pointer 87, located at the printing position, co-operates with the scale 85 to indicate the letter space position of the carriage. When the paper rack is 65 swung back the scale 85 may be lifted to the dotted line position to give access to the work on the erasing shelf as in Fig. 4.

70 75 It will be understood that although the invention may be used in connection with ordinary work sheets it may also be used for relatively stiff cards, such as index cards, and for stiff stencils.

80 85 In some classes of work the upper feed rollers may be used alone while the lower feed rollers remain released, but where it is desired to write 75

on the upper edge and the lower edge of a work sheet, both sets of feed rollers are used to feed it. For example, when it is desired to type to and including the lower edge of the work sheet it is 5 first fed by the lower feed rollers 16, 17. Before the lower edge reaches said feed rollers the upper feed rollers are rendered effective to grip the work sheet after which the lower feed rollers may be released by the handle 27 as previously described. 10 The work sheet may then be line spaced by the finger wheel 59.

Having thus described the invention, it should be understood that alterations and changes may be resorted to without departing from the spirit 15 of the invention as defined in the appended claims.

I claim:—

1. In a typewriting machine, the combination of a carriage, printing instrumentalities, two paper guides to embrace the sides of a work sheet to assist in guiding it in a flat condition downwardly to the printing instrumentalities, feed rollers for said work sheet above the printing instrumentalities, the bite of the feed rollers being in the plane in which the work sheet is guided by said guides, means to adjust the paper guides for various widths of work sheets, and means to adjust the feed rollers, accordingly, there being an open space between the two paper guides in which the 30 feed rollers are located.

2. In a typewriting machine, the combination of a carriage including two end pieces, printing instrumentalities, a frame supported on said carriage, said frame being located above the printing instrumentalities, said frame having two end members and a cross bar extending between and secured to said end members, a second cross bar on said frame, feed rollers on the last mentioned cross bar, a frame pivoted on the first mentioned 40 frame, feed rollers on the pivoted frame to co-operate with the first named feed rollers, side guides on the secured cross bar to direct a work sheet between the feed rollers, and pivot studs connecting said end members with said end pieces to pivotally support the first mentioned frame on said carriage to enable it to be swung to an ineffective position on said carriage.

3. In a typewriting machine, the combination of a carriage, printing instrumentalities, a frame pivoted on said carriage and extending above the printing point, a paper guide supported on said frame, an erasing shelf located at a lower level than the paper guide, said frame being swingable rearwardly to carry the work sheet over the erasing shelf, and a fixed detent on the carriage to engage the pivoted frame to hold the latter in both of its positions.

4. In a typewriting machine, the combination of a carriage frame, printing instrumentalities therefor, feed rollers supported on the carriage frame, a paper guide rack, two studs secured to said carriage frame to pivotally support the rack, an erasing shelf located behind the plane in which the rack is normally located, said rack being swingable rearwardly and downwardly about said studs from a normal vertical position to lay that portion of the work sheet above the feed rollers over the erasing shelf without disturbing the position of the feed rollers, and a detent secured to one of said studs and to engage the rack to hold the latter in its normal position.

5. In a typewriting machine, the combina-

tion of a carriage, printing instrumentalities therefor, a paper guide rack, two studs secured to said carriage to pivotally support the rack, an erasing shelf located behind the plane in which the rack is normally located, said rack being 5 swung rearwardly about said studs to carry the work sheet over the erasing shelf, one of said studs comprising a head and a shank, and a detent supported on the shank of said stud to engage the rack to hold the latter in its normal 10 position, said detent having an extension to engage the head of the stud to prevent rotation of the detent about the stud.

6. In a typewriting machine, the combination of a carriage, printing instrumentalities therefor, a paper guide rack, two studs secured to said carriage to pivotally support the rack, an erasing shelf located behind the plane in which the rack is normally located, said rack being 15 swung rearwardly about said studs to carry the work sheet over the erasing shelf, the rack including two end pieces by which it is supported on said studs, each stud comprising a shank by which it may be secured to the carriage, a bearing portion to support one of the end pieces of 20 the rack and a square head, and a detent supported on the bearing portion of one of the studs to engage the end piece to hold the rack in its normal position, said detent having two 25 ears bent off therefrom to engage the sides of 30 the square head of the stud to prevent rotation of the detent about the stud.

7. In a typewriting machine, the combination of a carriage, a frame secured thereto, said frame including an upper rod, a lower rod, and an intermediate rod, a feed roller on said lower rod, a frame pivoted on said upper rod, a feed roller on the pivoted frame to cooperate with the first mentioned feed roller and channel shaped guides on the intermediate rod to fit around the side 40 edges of a work sheet to direct said work sheet into the bite of said feed rollers.

8. In a typewriting machine, the combination of a carriage, a frame secured thereto, two paper guides adjustably mounted on said frame to- 45 wards and away from each other to accommodate different widths of work sheets, a feed roller located in the open space between said guides and mounted on said frame independently of said guides, a U-shaped frame including a cross- 50 bar and two arms extending upwardly therefrom, one at each end of said cross-bar, the U-shaped frame being pivoted at the upper ends of its arms on the first mentioned frame, a feed roller on said bar, and a spring to act on the U-shaped 55 frame to press the feed rollers together.

9. In a typewriting machine, the combination of a carriage, a frame secured thereto, two paper guides, a feed roller located between said guides on said frame, a U-shaped frame including a 60 cross-bar and two upwardly extending arms, one at each end of said cross-bar, the U-shaped frame being pivoted at the upper ends of its arms on the first mentioned frame, a feed roller on said bar, a spring to act on the U-shaped 65 frame to press the feed rollers together, said arms having each an extension below said rod, and a scale bar located below the feed rollers and secured to said extensions to assist in setting the paper guides endwise of the carriage.
